CLAIM

The ornamental design for a security tag, as shown and described.

DESCRIPTION

FIG. 1 is a perspective view of a security tag showing my new design;

FIG. 2 is a bottom perspective view of the design shown in FIG. 1;

FIG. 3 is a left side view of the design shown in FIG. 1;

FIG. 4 is a right side view of the design shown in FIG. 1;

FIG. 5 is a front view of the design shown in FIG. 1;

FIG. 6 is a rear view of the design shown in FIG. 1;

FIG. 7 is a top view of the design shown in FIG. 1; and,

FIG. 8 is a bottom view of the design shown in FIG. 1.

The broken lines shown in the figures are included for the purpose of illustrating portions of the security tag and form no part of the claimed design.

1 Claim, 8 Drawing Sheets(56)
